UNITED STATES PATENT OFFICE.

WILLIAM C. NORTH, OF CLEVELAND, OHIO.

DESIGN FOR A BODY-LOOP BOLT.

SPECIFICATION forming part of Design No. 31,749, dated October 31, 1899.

Application filed October 9, 1899. Serial No. 733,108. Term of patent 14 years.

To all whom it may concern:

Be it known that I, WILLIAM C. NORTH, a citizen of the United States, residing in Cleveland, in the county of Cuyahoga and State 5 of Ohio, have invented and produced a new and original Design for a Body-Loop Bolt, of which the following is a specification, reference being had to the accompanying drawings, forming part thereof.

- Figure 1 is a plain elevation of my design, and Fig. 2 is a longitudinal sectional elevation thereof.

As shown in the drawings, the leading or material features of my design consist, es- 5 sentially, in the appearance of the bolt as a whole, which appearance, when more specifically examined, discloses a bolt-head with an artistic exterior 2, spiral ornamentation

3 on its opposite end, and an intermediate shank relieved by a series of parallel grooves 20 and ribs 4 alternately in its lower portion, the ribs standing out somewhat beyond the adjacent surfaces of the shank, and the shank having a plane surface 5 next below the head, the head itself having an appreciable 25 convexity about the shank, as more plainly disclosed in section, Fig. 2.

What I claim is—

The design for a body-loop bolt, substantially as shown and described. 30

Witness my hand to the foregoing specification this 28th day of September, 1899.

WILLIAM C. NORTH.

Witnesses:

H. E. MUDRA,
R. B. MOSER.
